ROBERT A. LACKEY, OF OAK PARK, ILLINOIS.

WINDOW-OPERATING MECHANISM.

1,112,072.

Specification of Letters Patent. Patented Sept. 29, 1914.

Application filed May 16, 1910. Serial No. 561,778.

To all whom it may concern:

Be it known that I, ROBERT A. LACKEY, a citizen of the United States, residing at Oak Park, in the county of Cook and State 5 of Illinois, have invented certain new and useful Improvements in Window-Operating Mechanisms, of which the following is a specification.

This invention relates to window operating mechanisms by means of which a series 10 of windows are automatically operated so as to be simultaneously opened and closed.

The invention has for one of its objects, the provision of a mechanism which shall 15 be simple in construction, cheap to manufacture and easy to install, and which will open all of a series of windows to the same extent and will likewise close them all tightly at the same time without leaving 20 some of the windows partially open.

Another object of the invention is the provision of a device of this character, which shall be efficient in its operation and which will utilize advantageously the force 25 applied to it with the least degree of frictional resistance and strain upon the mechanism.

Additional objects and advantages of the invention will become apparent as it is better understood by reference to the following 30 description when taken in connection with the accompanying drawings illustrating a preferred embodiment thereof.

Referring to the drawings—Figure 1 is a plan view of a structure embodying my invention, on line 1—1 of Fig. 2. Fig. 2 is a front elevation of a portion thereof; and Fig. 3 is a section on the line 3—3 of Fig. 2.

Referring to the drawings, 4 represents 40 a portion of the wall of a building in which there are arranged a series of window sashes 5. The sashes are shown as pivotally mounted at or near their centers to swing about a horizontal axis; the upper portion 6 of 45 the window jamb being located outside the sash and the lower portion 7 located inside the sash to permit the bottom of the windows to swing outwardly and the top inwardly. It will be understood, however, 50 that the windows may be mounted in any other preferred manner, as for instance by hinging them at the top so that the bottom may be swung outwardly by my improved operating mechanism, or by hinging them 55 either at the top and bottom or at one side so as to swing in a vertical plane. Affixed

to each section of the wall between the adjacent windows of the series, is a bracket or supporting block upon which are mounted at 9, a pair of pivotal members 10. As will be evident from Fig. 1, the brackets 8 project at either end a short distance beyond the edge of the wall section, and the pivotal members are mounted near the extremities of the brackets so as to be capable of swinging outwardly on their pivots into the window openings without striking against the edges of the wall section.

Each window sash has secured thereto near each side, a pivot plate 11. A link 12 is pivoted at one end in said pivot plate and pivoted at the other end to the outer end of the adjacent pivotal member 10. The pivotal connections between the link 12 and the pivotal member 10, and the pivot plate 11, are designed to afford sufficient play to permit the window sash to be swung outwardly and upwardly about its pivotal bearing without cramping or binding the link 12.

A pair of operating rods 13 and 14 extend longitudinally of the series of windows and are supported so as to be capable of longitudinal movement in suitable bearings provided in the brackets 15. The operating rods are shown on the drawings as being round, but it will be evident that they may be made square, triangular or any other preferred shape, and that the bearings in which they are adapted to move longitudinally may be constructed to accommodate the particular shape of rods employed and permit them to slide freely therein. A plurality of collars 16 are adjustably secured upon each of the rods, said collars having laterally projecting portions adapted to receive the ends of links 17 pivotally attached at their other ends to the pivotal members 10. The upper operating rod 13 is connected by every alternate link 17 with each of the pivotal members 10 disposed at the right of a window opening, viewing Figs. 1 and 2, while the lower operating member 14 is pivotally connected by means of the remaining links 17 with the pivotal members 10 mounted at the left of the window openings.

It will be evident from the above construction, that longitudinal movement of the operating rod 13 to the left viewing Fig. 1, will swing the pivotal members attached at the right side of the window sashes upon their pivots into the dotted line position shown in Fig. 1, and that simultaneous lon-

5 longitudinal movement of the operating rod 14 in the opposite direction will swing the remaining pivotal members 10 upon their pivots into the dotted line position shown. By 10 connecting the pivotal members to the operating rods by means of links, as described, the pivotal members are enabled to swing through nearly an arc of 180° thereby nearly doubling the range of movement of the windows over constructions which pivotally connect the operating rods directly to the pivotal members, thereby limiting the movement of the pivotal members between positions perpendicular to and parallel with the 15 window or to an arc of 90° . Simultaneous movement of the operating rods in opposite directions, is accomplished by connecting the rods together at both ends to any suitable type of operating mechanism.

20 I have shown for the purposes of illustration merely, one form of operating mechanism comprising a chain 18 passed over a sheave 19 and attached at one end to the operating rod 13 and at its other end to the 25 operating rod 14. The sheave 19 may be rotated by any preferred form of operating mechanism to simultaneously move the operating rods longitudinally in opposite directions.

30 Simultaneous swinging movement of the pivotal members 10, serves, through the intermediary of the connecting links 12, to operate both sides of the windows simultaneously and equally, thereby overcoming 35 any tendency of wide windows to stick, such as usually exists in connection with operating mechanisms leaving but one point of attachment to windows of considerable width. For narrower windows, however, one point 40 of connection may be found sufficient, in which instance but one operating rod would be employed and half of the connections could be dispensed with.

45 By connecting the operating rods to the windows in the manner above described, the greatest force is exerted upon the windows when they are practically closed, *i. e.*, the mechanism is capable of exerting the greatest amount of force upon the windows when 50 the parts are in the position shown in full lines in Fig. 1; and since any opposition to the movement of the windows occasioned by sleet, snow or sticking of the windows, always occurs when the windows are in substantially closed position, the greatest efficiency of my mechanism is derived at the 55 time when it is most needed. It will be evident also, that the farther out into the window openings the pivotal members 10 are 60 swung during the opening operation, the more nearly the links 17 approach a perpendicular to the operating rods, and that the nearer the links approach the perpendicular, assuming that the operating rods 65 are moved at a constant speed, the faster the

outer ends of the pivotal members and consequently the windows, will be moved. This is a very desirable feature in window operating mechanisms for the reason that after the windows have been started from the frames but little resistance is offered to their movement, and power which was very essential in starting the windows becomes a secondary factor in importance to speed during the remainder of the movement. My improved operating mechanism is so constructed that the power applied thereto, is utilized to the best advantage to exert the greatest force upon the windows in initiating the opening and completing the closing movements, and to move the windows at accelerated speed during the remaining portion of their movement. Another advantage of my construction resides in the fact that the weight of the windows when in open position, is distributed between the pivotal members 10 and the links 12, thus relieving the operating rods of a large part of the lateral thrust thereon occasioned by the weight of the open windows.

90 While I have shown and described a preferred embodiment of my invention, it will be apparent that various minor mechanical changes may be resorted to without departing from the spirit of the invention or sacrificing any of the material advantages thereof.

95 What I claim is:

1. In a window operating mechanism, the combination of a straight member pivoted adjacent a window to be operated, so that its free end will swing outwardly beyond the window frame, a link connecting said member with said window and normally disposed at an angle to the plane of the closed window, an operating rod mounted to reciprocate longitudinally, and an oscillating connection between the outer end of said member and the rod to cause said member to swing on its pivot through an arc greater than 90° .

100 2. In a window operating mechanism, the combination of a series of members pivoted adjacent a series of windows to be operated so that the free ends of said members will swing outwardly beyond the window frames, a link connecting each of said members with a window, said links being normally disposed at an angle to the plane of the closed windows, an operating rod mounted to reciprocate longitudinally in a direction parallel with the windows, and a link connecting the ends of each of said members with said rod whereby longitudinal movement of the rod will swing the members upon their pivots through an arc greater than 90° to operate said windows.

105 3. In a window operating mechanism, the combination of a series of straight members pivoted adjacent a series of windows to be

operated, said members being normally disposed at right angles to the plane of the closed windows, a series of links connecting said windows with the adjacent members, 5 an operating rod mounted to reciprocate longitudinally only, and a series of links connecting said members with said rod whereby the outer ends of said links will travel from one side of said rod to the other 10 and the pivotal members may be swung on their pivots in an arc of approximately 180° so that their free ends are swung outside the window frames to operate said windows upon longitudinal movement of said operating rod.

4. In a window operating mechanism, the combination of a series of windows, a member pivoted adjacent each side of a window to be operated and extending inwardly 20 therefrom, a link connecting each of said members with a side of a window, a pair of operating rods mounted to move simultaneously in opposite directions, and an oscillatory connection between each rod and a 25 number of said members to cause said members to oscillate simultaneously transversely of said rods to operate the window upon actuation of the rods.

5. In a window operating mechanism, the 30 combination of a member pivoted adjacent each side of a window to be operated, a link connecting each of said members with a side of the window, a pair of operating rods mounted to move simultaneously in opposite 35 directions, and an oscillatory connection between each member and a rod, each of said connections comprising a link pivotally connected at one end to a rod and at the other end to one of said members whereby 40 to cause said members to oscillate simultaneously to operate the window upon actuation of the rods.

6. In a window operating mechanism, the 45 combination of a member pivoted adjacent each side of a window to be operated and extending inwardly therefrom, a link connecting each of said members with the window, a pair of operating rods mounted to move longitudinally only, and a link connecting each of said rods with one of said 50 pivotal members and permitting said members to oscillate on their pivots transversely of the rods.

7. In a window operating mechanism, the 55 combination of a pair of members pivoted adjacent a window to be operated and extending inwardly therefrom, means for connecting said members to the window, a pair of operating rods mounted to move in a longitudinal direction only, and means pivotally connecting each rod with a pivotal member whereby longitudinal movement of the rods in opposite directions will swing the pivotal members on their pivots to operate the window.

8. In a window operating mechanism, the combination of a series of oscillatory members pivoted adjacent the edges of a series of windows to be operated, a link connecting each member with a side of a window, a plurality of longitudinally movable operating rods mounted to reciprocate simultaneously in opposite directions, links connecting alternate members of said series with one of said operating rods, and links connecting the 70 remaining members of the series with the other operating rod whereby longitudinal movement of the rods will actuate said members to operate the windows.

9. In a window operating mechanism, the combination of a series of oscillatory members pivoted adjacent the sides of a series of windows to be operated, a pair of operating members mounted to reciprocate longitudinally in opposite directions, connections between alternate members of said series and one of said operating members, connections between the remaining members of the series and the other operating member, said connections comprising links pivoted at one end 80 to the operating members and at the other end to the oscillatory members, and a connection between each of said oscillatory members and a side of a window of the series whereby the windows will be operated upon 85 movement of the operating members.

10. In a window operating mechanism, the combination of a plurality of members pivotally mounted adjacent the sides of a series of windows to be operated and extending inwardly therefrom, a link connecting each member with the adjacent side of a window, a pair of operating rods mounted to be moved in a longitudinal direction only, links pivotally connecting alternate members of said series with one of said rods, whereby longitudinal movement of the rods in opposite directions will swing the members upon their pivots to operate the windows.

11. In a window operating mechanism, the combination of a series of windows, a horizontally disposed member pivoted adjacent each side of each window to be operated, a link connecting each of said members with a side of a window, a pair of operating rods mounted to simultaneously move longitudinally in opposite directions, and an oscillatory connection between each rod and alternate members to cause the said members to oscillate simultaneously to actuate each 110 member to open and close the window.

12. In a window operating mechanism, the combination of a member pivoted adjacent each side of the window to be operated, an operating rod for each member mounted to move longitudinally, and a pair of links pivotally connected adjacent an end of each member, one of said links being pivotally connected to the side of a window and the other to an appropriate operating rod.

13. In a window operating mechanism, the combination of a series of windows, a pair of members pivoted between adjoining edges of a pair of windows, an operating rod 5 mounted to move longitudinally, a pair of links pivotally secured to an end of each member, one of said links being pivotally connected to its adjacent window and the other link being pivotally connected to the 10 operating rod in front of the other window.

14. In a window operating mechanism, the combination of a series of oscillatory members pivoted adjacent a series of windows to be operated, a link connecting each member 15 with a side of a window, a pair of longitudinally movable operating rods mounted to reciprocate simultaneously in opposite directions, one of said rods being disposed above and the other beneath the said oscillatory members, links connecting said members with the said rods whereby longitudinal 20

movement of the rods will actuate the members to operate the windows.

15. In a window operating mechanism, the combination of a series of oscillatory members pivoted adjacent a series of windows to be operated, a link connecting each member with a side of a window, a pair of longitudinally movable operating rods mounted to reciprocate simultaneously in opposite directions, said operating rods being disposed inwardly of the free ends of the said oscillatory members, and one of said rods being disposed above and the other beneath said oscillatory members, and links connecting the said members with the said rods whereby longitudinal movement of the rods will actuate the said members to operate the windows 30
